DESIGN FOR A BOTTLE

Frank W. Bireley, Los Angeles, Calif., assignor to Bireley's Inc., Los Angeles, Calif., a corporation
of California

Application January 11, 1936, Serial No. 60,534

Term of patent 14 years

To all whom it may concern:

Be it known that I, Frank W. Bireley, a citizen of the United States, residing at Los Angeles, county of Los Angeles, and State of California,
have invented a new, original, and ornamental Design for a Bottle of which the following is a specification, reference being had to the accompanying drawing, forming a part thereof.

The figure is an elevational view of a bottle showing my new design. The reverse side is identical with the side illustrated in the drawing.

I claim:

The ornamental design for a bottle as shown
and described.

FRANK W. BIRELEY.
